E. P. COLE,
SAFETY LOCK FOR OVEN BURNERS,
APPLICATION FILED JULY 26, 1920.

1,405,186.

Patented Jan. 31, 1922.

UNITED STATES PATENT OFFICE.

EDWARD P. COLE, OF CHICAGO, ILLINOIS, ASSIGNOR TO COLE MANUFACTURING COMPANY, OF CHICAGO, ILLINOIS, A CORPORATION.

SAFETY LOCK FOR OVEN BURNERS.

1,405,186.

Specification of Letters Patent. Patented Jan. 31, 1922.

Application filed July 26, 1920. Serial No. 398,951.

To all whom it may concern:

Be it known that I, EDWARD P. COLE, a citizen of the United States, and a resident of Chicago, in the county of Cook and 5 State of Illinois, have invented certain new and useful Improvements in Safety Locks for Oven Burners, of which the following is a specification.

The invention has reference more particularly to a safety lock for oven burners and seeks to provide a simple construction arranged to prevent the opening of the supply valve and the admission of gas to the oven burner unless the door of the oven has 15 been previously opened.

Further objects of the invention are to provide a locking device operating with the gas supply valve and engaged by the door when the latter is in a closed position so 20 as to prevent operation of the valve and necessitating opening of the door before the valve can be moved from the closed position; to provide a valve locking device which interlocks with the door to hold the 25 valve closed and which is entirely disengaged from the door in the open positions of the valve; to provide a valve locking device which is moved to the released position upon a slight opening movement of the 30 valve and having a limited movement thereafter, so that the valve has a large range of adjustment, from a slight open position to a clear open position, without material operation of the locking device or danger 35 of the locking device becoming re-engaged with the door; to provide a locking device adapted to interlock with the marginal edge of the door and wherein such marginal edge serves to guide the locking device to the 40 locking position; and, in general, to provide an improved locking device for the valve of an oven burner which interlocks with the door, and is of simple form and adapted to be applied to the ordinary gas range construction without material alterations or 45 changes or special provision to render the locking device capable of being applied thereto.

In the drawings, Fig. 1 is a side view of 50 a range having my invention applied thereto;

Fig. 2, an enlarged view of the valve locking mechanism in the released position;

Fig. 3, a top view, partly in section, of 55 the mechanism shown in Fig. 2, the locking

member, however, being shown engaged with the door; and

Fig. 4, a front view, of the interengaging portions of the valve lever, and locking dog in the locking position.

The stove or range 1 has an oven 2 provided with a door 3 that is pivoted at its lower edge in a pair of lugs 4. A gas supply pipe 5 communicates through a valve 6 with the burner 7 in the bottom of the 65 oven for heating the latter. A valve operating stem 8 extends outwardly through a side bracket 9, has a shoulder 10 journaled in the bracket and a handle 11 at its outer end. The bracket 9 forms in effect an extension of the front wall of the stove.

A locking dog 12 is pivoted adjacent the axis of the stem 8 on a stud 13 which projects outwardly from the bracket 9 and the outer end of this dog is arranged to engage 75 a notch 14 in the beveled or rounded edge of the oven door 3. This notch forms an abrupt shoulder that is adapted to abut against the end of the dog and prevent its movement while the door is closed.

Formed on the stem 8, adjacent the outer face of the bracket 9 is a finger 15 which, in the closed and locked position of the valve, 6 fits in a notch 16 in the outer end of the dog 12 and lies alongside and in 85 reverse position to a finger 17 with which the dog is provided at one side of the notch. At the other side of this notch is a short finger 18 for preventing the finger 15 from passing out of the notch at that side.

When the oven door 3 is closed and the valve handle 11 is in the off-position, the end of the dog 12 engages in notch 14, and the finger 15 of the valve stem engages the notch 16 of the dog (see Figs. 1 and 4) so 95 that the valve is locked in its closed or off-position. When, however, the door is opened, the dog and valve handle are released and the latter can be shifted to open the valve. The opening movement of the valve stem moves the finger 15 thereof out of the notch 16 and against the finger 17 of the dog 12 so that the latter is shifted out of the path of movement of the door which may then be opened and closed without engaging the locking device in any manner.

It is desirable that the valve 6 may have a large range of adjustment from the point in which it is nearly closed to the fully open 110

position without engaging the locking dog 12 with the door. In the closed and locked positions of the valve, the cooperating fingers 15 and 17 are substantially parallel and in line with the pivotal axes of the valve stem 8 and dog 12, so that a slight opening movement of the valve stem causes a considerable throw of the inner end of the dog 12 to move it well away from the edge of the door. After such preliminary movement, further operation of the valve stem effects very little movement of the dog, since the finger 15 is then substantially at right angles to the finger 17 and merely slides along its surface. In other words, the initial movement of the valve effects an accelerated movement of the dog and thereafter effects a retarded movement.

The locking mechanism is enclosed by a cover plate 19 which is secured in position by bolts 20, or in any other suitable manner, and through which the outer end of the valve stem 8 extends. An inturned flange 21 about the edges of the plate holds the latter away from the outer faces of the stove and of the bracket 9, and this flange is cut away adjacent the oven door 3, so that the end of the dog 12 projects beyond the cover plate and has the necessary freedom of movement.

In returning the valve to off-position, the finger 15 at the end of the valve closing movement acts on the finger 18 and moves the dog 12 to the locking position. If this occurs when the door is closed, the end of the dog must yield in some manner and ride over the edge of the door into the notch 14. In the present construction this is accomplished by counter-sinking the aperture 22 of the dog in which the pivot stud 13 is engaged so that a limited rocking movement of the end of the dog to and from the wall of the stove is permitted. The cover plate 19 which serves to hold the dog in position on the stud 13 is spaced so as to permit this movement, and the outer end of the dog has a rounded cam surface on the underside, as indicated at 23, so that as the valve handle 11 is thrown to the closed position and the dog 12 swings on its pivot stud 13, the end of the dog engages the beveled or rounded edge of the door 3 and rides up over the edge until it reaches a point where it may drop into the notch 14.

From the foregoing, it will be observed that I have provided a simple locking device for the supply valve of the oven burner, which prevents opening the valve when the door is closed and which is entirely disengaged from the door and offers no interference to the operation of the latter when the gas supply valve has been preliminarily opened; that the locking device is so shifted upon a very slight preliminary movement of the valve handle, that a large range of

adjustment of the valve from the fully open position to a nearly closed position is permitted, without danger of re-engagement of the locking device; that the improved construction may be readily applied to existing types of ranges without material change or alteration, and requires only a few parts, which may be readily assembled, to afford a substantial and satisfactory valve locking device.

Obviously changes may be made in the details set forth without departure from the essentials of the invention as defined by the appended claims.

I claim as my invention:

1. In a stove, the combination with an oven having a door, a gas burner for heating the oven and a controlling valve for said burner, of a device adapted to interlock with the door to prevent the opening of the valve when the door is closed and means actuated by said valve adapted, upon its initial opening movement, to shift said device to a position entirely clear of the door and to restore the same into operative engagement therewith upon the final closing movement of the valve.

2. In a stove, the combination with an oven having a door, a burner for heating the oven and a controlling valve for said burner, of a locking device arranged to engage the door in its closed position and prevent the opening movement of said valve, the latter having means arranged to shift and hold said locking device entirely clear of the door when the valve is open and to restore the same into operative engagement with the door upon the final closing movement of the valve.

3. In a stove, the combination with an oven having a door, a burner for heating the oven and a valve controlling the supply of fuel to the burner, of a locking dog for said valve adapted to be moved into and out of the path of movement of the door as the valve is closed and opened, said door having a shoulder arranged, in its closed position, to engage said dog and to prevent the opening movement of said valve, and said door and said dog having co-operating surfaces adapted to deflect the dog past said shoulder and permit its re-engagement therewith upon the final closing movement of the valve.

4. In a stove, the combination with an oven having a door, a burner for heating the oven and a valve for controlling the supply of fuel to said burner, of a pivoted locking dog, the stem of said valve having a lug arranged to engage said dog and swing it back and forth upon its pivot, the door having a shoulder arranged, in its closed position, to engage said dog and prevent the opening movement of the valve, and said door and said dog having co-operating cam

surfaces adapted to deflect the latter from its normal path of movement and permit its re-engagement with said shoulder.

5. In a stove, the combination of an oven having a door, a burner for heating the oven, a valve for controlling the burner, a locking dog operable with the valve and engaging the door in the closed position for holding the valve in the closed position, said door having a notch in its edge to receive the dog and having means for deflecting the dog from its normal path of movement to admit the latter into the notch.

6. In a stove, the combination of an oven, a wall at one side of the oven having an opening therethrough to afford access to the oven, a door closing the opening, a burner for heating the compartment, a valve for controlling the burner and having an operating handle projecting through the wall, and a locking device pivotally mounted on the outer face of the wall to swing in a path substantially parallel to the plane of the door opening and adapted to interlock with the 25 edge of the door and said valve handle to prevent the opening movement of the valve when the door is closed.

7. In a stove, the combination with an oven, a door therefor, a burner for heating

the oven and a supply valve for said burner, 30 of a locking dog arranged to be shifted by said valve as the latter is opened and closed, said door having a notch arranged, in the closed position of the door, to receive the end of said dog and thereby lock the valve 35 in closed position, and said door having a beveled edge arranged, as the valve is closed, to deflect the dog from its normal path of movement to admit the latter in said notch.

8. In a stove, the combination with an oven, a door therefor, a burner for heating the oven and a supply valve for the burner, of a pivoted locking dog and a pivoted valve stem having co-operating lugs arranged substantially in line between the pivotal axes 45 thereof when the valve is closed, and substantially at right angles to each other when the valve is open, said dog being arranged to interlock with the oven door when the latter and said valve are closed to prevent 50 the opening movement of the valve, and said lugs co-operating to shift said dog clear of the door upon the initial opening movement of the valve and re-engage the same therewith upon its final closing movement.

Chicago, Illinois, July 22nd 1920.

EDWARD P. COLE.
